UNITED STATES PATENT OFFICE

2,557,300

GUARD FENCE FOR WELL PUMPING UNITS

Michael J. Lowry, Los Angeles, Calif.

Application July 9, 1949, Serial No. 103,826

3 Claims. (Cl. 256—21)

1

This invention relates to a guard fence for enclosing the usually large and heavy crank structures and associated moving parts of the pumping units of wells, particularly oil wells, so as to prevent injury of workers or persons who otherwise might get too close to such units, it being noted that the laws of many states require safety fences or like guard structures for such well pumping units.

The primary purpose of the present invention is to provide a guard fence, for the purpose above noted, which is constructed and arranged to prove superior to guard fences or guard structures heretofore employed in point of simplicity of construction, inexpensiveness of production and installation, lending itself to economical production and installation in sizes adaptable to different types of pumping units, ease of installation and removal without the use of bolts and other extraneous fastenings and its sturdiness and durability.

A more specific object is the provision in a sectional guard fence such as described of novel base units which are constructed to be readily fixed on the base structure of the pump unit and to serve as foundation means for removably supporting sections of the fence in properly assembled relation without the use of fastening elements such as bolts, rivets or the like.

Another specific object of this invention is the provision of a novel and simple means of detachably connecting two of the fence sections with one another and with the two base units of the fence wherein no separate or extraneous fastenings are required, assembly of the fence sections to vary the height of the fence is afforded and a quicker and easier installation and taking down of the fence is made possible.

With the foregoing objects in view, together with such other objects and advantages as may subsequently appear, the invention resides in the parts and in the combination, construction and arrangement of parts hereinafter described and claimed and illustrated by way of example in the accompanying drawing, in which:

Fig. 1 is a perspective view of a guard fence embodying my invention, as installed in connection with a well pumping unit;

Fig. 2 is an enlarged fragmentary top plan view of the fence, with the sections of the fence broken away for clarity of illustration;

Fig. 3 is a further enlarged fragmentary elevational view partly in section of one lower corner as it would appear in looking in the direction of the arrow 3 in Fig. 1;

2

Fig. 4 is an enlarged fragmentary elevational view partly in section as seen from the line 4—4 of Fig. 2;

Fig. 5 is an enlarged exploded, fragmentary, perspective view showing the manner of assembling the fence; and

Fig. 6 is a fragmentary horizontal sectional view taken on the line 6—6 of Fig. 3.

Referring to the drawings more specifically Fig. 1 thereof shows a guard fence A embodying my invention as set up around a well pumping unit of the type used for pumping oil wells. This pumping unit includes a base structure B supporting a drive means C for a crank unit D which latter operates the walking beam E through driving links F.

My improved guard fence, in one form, as here shown is rectangular and includes a pair of like rectangular side sections 7 and 8, a rectangular end section 9 for one end of the fence and a pair of like rectangular end sections 10 and 11 for forming the other end of the fence with a central gap or space for drive connection, not shown, between the prime mover, also not shown, and the drive means C for the crank unit D. These fence sections when put up as shown in Fig. 1 serve to prevent workers and persons from being injured by getting too close to the crank structure D and associated moving parts of the pump unit.

Each of the several sections, there being in this instance five, is formed of a suitable meshed body 12 made of a panel of wire or expanded metal to afford desired visibility therethrough plus weight reduction, which body is fixed to and bordered by a rectangular angle iron frame 13. The side sections 7 and 8 have the lower corners cut away as at 14 to accommodate a particular joining of the sections of the fence as will be hereinafter described.

In accordance with my invention I provide as a base for the fence, a pair of angle iron base rails 15 and 16 which are adapted to be fixed, as by being welded, to the base structure B of the pumping unit, so as to extend horizontally across the base structure on opposite sides of the crank unit D and associated moving parts and in such spaced relation to one another as to suit the particular dimensions of the side sections 7 and 8 for the particular pump unit.

Welded or otherwise fixed as 15 and 16 or at such points on the rails best suited to the particular dimensions of the sections of the fence, are like upright channel-shaped and open-ended keeper members 17 with their open sides opposed so that the lower corner portions of the

end section 9 and the outermost lower corners of sections 10 and 11 may be lowered into the channels of the keeper members with the frames 13 of said sections fitted therein as shown in Fig. 6. The inner lower corners of the spaced end sections 10 and 11 are received in like channeled keepers members 18 fixed to the base rail 15 in the same manner as the keepers 17.

As a means for limiting the seating, that is, the downward extension of the end sections 9, 10 and 11 in the keeper members 17 and 18, the frames 13 for said sections are provided with stop lugs 19 welded thereto so as to abut the tops of said keeper members as best shown in Fig. 3.

As a means for connecting the end sections 9, 10 and 11 with the side sections 7 and 8 and the latter with the keeper members 17, the side sections are provided adjacent the upper and lower ends of the end members of their frames 13 with downwardly facing hooks or pintles 20 and 21 which are welded or otherwise fixed thereto and adapted to be fitted into eyes or apertured members 22 and 23 fixed in like manner to the upper ends of the side members of the frames 13 of the end sections 7 and 8 and to the keeper members 17 respectively. This connecting of the upper portions of the end sections 9, 10 and 11 with the side sections 7 and 8 provided for by means of pintles 20 and the eyes or apertured members 22 while the lower ends of the side members are connected to the upright keeper members 17 by means of the pintles 21 and apertured members 23, ties the sections together securely and provides a rigid and durable fence which can be much more readily, easily and inexpensively installed and taken down than fences as heretofore provided.

It will now be seen that an efficient fence embodying my invention may consist of but five fence sections and two base rails units which latter include the keeper members 17 and 18 fixed thereto and that these parts may be packed and shipped in comparatively small compass and are subject to being readily and easily set up on the job without the use of bolts and other extraneous fastening.

The operation of installing the fence simply requires that the two base rails 15 and 16 be fixed, for example, as by being welded, to the base structure of the pump unit and thereafter the end sections 9, 10 and 11 are fitted into the keeper members 17 and 18 and thus held upright, following which the side sections 7 and 8 are easily lowered into proper position to cause the pintle thereon to fit into the eyes 22 and 23 on the end sections and keeper members 17 respectively.

I claim:

1. In a guard fence for a well pumping unit, a plurality of end sections for forming the ends of a substantially rectangular fence, side sections adapted to be joined to the end sections to form the sides of said rectangular fence, rails adapted to be fixed to the base structure of the pumping unit so as to extend horizontally in spaced op-

posed relation to one another, keeper members of channel shape in cross section fixed to upright position to said rails in the channels of which the lower ends of said end sections are removably socketed to hold the end sections upright, hook members on said side sections; and apertured members on said end sections and keeper members respectively detachably receiving said hook members to hold the sections assembled as a fence.

2. In a guard fence for a well pumping unit, a plurality of end sections for forming the ends of a substantially rectangular fence, side sections adapted to be joined to the end sections to form the sides of said rectangular fence, rails adapted to be fixed to the base structure of the pumping unit so as to extend horizontally in spaced opposed relation to one another, keeper members of channel shape in cross section fixed to upright position to said rails in the channels of which the lower ends of said end sections are removably socketed to hold the end sections upright, apertured members on said end sections and said keeper members respectively, and downwardly facing hooks on said side sections engaged with said apertured members for detachably connecting said side sections to said end sections and detachably connecting said side sections to said keeper members.
3. In a guard fence for a well pumping unit, a plurality of end sections for forming the ends of a substantially rectangular fence, side sections adapted to be joined to the end sections to form the sides of said rectangular fence, rails adapted to be fixed to the base structure of the pumping unit so as to extend horizontally in spaced opposed relation to one another, keeper members of channel shape in cross section fixed to upright position to said rails in the channels of which the lower ends of said end sections are removably socketed to hold the end sections upright, stop members on said end sections for contacting the upper ends of said keeper members to limit the extension of said end sections into said keeper members, and means for detachably connecting the ends of said side sections to said end sections and said keeper members respectively.

MICHAEL J. LOWRY.
